UNITED STATES PATENT OFFICE.

OLOF WILLIAM ORELL, OF ST. LOUIS PARK, MINNESOTA.

RUB-IRON.

SPECIFICATION forming part of Letters Patent No. 590,235, dated September 21, 1897.

Application filed February 1, 1897. Serial No. 621,559. (No model.)

To all whom it may concern:

Be it known that I, OLOF WILLIAM ORELL, a citizen of the United States, and a resident of St. Louis Park, in the county of Hennepin 5 and State of Minnesota, have invented certain new and useful Improvements in Rub-Irons; and I do hereby declare that the following is a full, clear, and exact description of the invention, which will enable others skilled in the art to which it appertains to make and use the same, reference being had to the accompanying drawings, which form a part of this specification.

My invention relates to rub-irons adapted 15 for use in connection with whiffletrees for preventing injury to the latter when striking the wheel of a vehicle; and its object is to provide an improved construction of the same which shall possess superior advantages with 20 respect to efficiency in use.

The invention consists, essentially, in a spring-metal plate provided at each end with a outwardly-extending lug formed with a semicylindrical recess at each end, a hole for 25 the passage of a screw, and a recess in the inner side, in combination with a roller having a journal at each end fitting in said last-named recesses, and said roller being sprung into place and held in position by the resiliency 30 of said plate, as hereinafter fully described.

In the accompanying drawings, Figure 1 is 35 an elevation of one end of a whiffletree, showing my improved rub-iron secured thereto. Fig. 2 is a sectional view of the same. Fig. 3 is a longitudinal sectional view of the plate detached from the whiffletree and the roller removed. Fig. 4 is a plan view of the plate.

In the said drawings the reference-numeral 1 designates a whiffletree of any ordinary or 40 suitable construction, cut away at 2 near one end, forming a curved surface.

The numeral 3 designates a spring-metal plate having formed integral therewith at each end a curved or beveled lug 4, projecting outwardly from said plate and formed 45 with screw-holes 5. The inner adjoining sides of said lugs are formed with recesses 6 to receive the journals of a roller, hereinafter described. The under sides of said plates or

lugs at the ends are formed with semicylindrical recesses 7, which fit upon the curved or rounded portions of the whiffletree at the ends of the cut-away portion 2. The under side of said plate is flat, while its upper side tapers from the lugs at the ends to the center 55 and is formed with two holes 3^a to receive set-screws 3^b.

The numeral 8 designates a roller formed with a stud or journal 9 at each end, which fits in the recesses 6. The said roller is connected with the recesses 6 by bending the plate 1 backward sufficiently to allow the studs 9 to pass the lugs when the plate is let go, springing back into normal position, when the studs will enter the recesses and the roller be held 65 in place by the resiliency of the plate.

The device is secured to the whiffletree by means of screws 10, the flat under side seating on the cut-away portion of the whiffletree and the semicylindrical ends fitting on the curved 70 portion.

In use when the traces become slack or in turning the roller will strike the wheel, instead of the whiffletree doing so, as is ordinarily the case, and injury to the whiffletree 75 by rubbing or striking the wheel is obviated.

In case the journal 6 should wear so as to work too loose in the recesses in the lugs, by loosening the screws 5 at the ends of the plate and tightening the screws 3^b at the center the 80 central portion of the plate will be depressed, drawing the lugs inward, so as to take up the wear of the lugs and prevent rattling.

Having thus described my invention, what I claim is—

1. In a rub-iron for whiffletrees, the combination with the flat spring-metal plate having semicylindrical recesses at each end on the under side, the lugs formed with screw-holes and with recesses in the inner sides, of 90 the roller, having a journal or stud at each end sprung into place and held in position by the resiliency of the said plate, substantially as described.

2. The combination with a whiffletree provided near the end with a curved recess, of the spring-metal plate, flat on its inner side and formed with semicylindrical recesses at 95

the ends and tapering on its upper side, the lugs formed with recesses at the inner sides, the roller having a lug at each end journaled in said recesses, the screws at the ends of said plate and the set-screws at the center thereof, substantially as and for the purpose specified.

5 In testimony that I claim the foregoing as

my own I have hereunto affixed my signature in presence of two witnesses.

OLOF WILLIAM ORELL.
